CONTINUOUS AUTOMATIC MACHINE FOR PROVIDING A PERMANENT CURVATURE ON THE EXTREME EDGES OF COVERS FOR BOOK MATCHES WITH SNAP CLOSURE

Pietro Molla, Pontenuovo di Magenta, Italy, assignor to S.A.F.F.A. Societa per Azioni Fabbriche Fiammiferi ed Affini, Milan, Italy, a corporation of Italy

Filed Apr. 26, 1955, Ser. No. 504,056

Claims priority, application Italy Oct. 2, 1954

7 Claims. (Cl. 18—19)

It is known that some types of book matches have a rectangular cardboard cover with one or both extreme edges permanently curved so as to provide an easy and safe closure of the booklets, which is obtained by a light pressure applied by the fingers on the external faces of the booklet.

Such types of booklets are, for example, those described in the U.S. Patent No. 2,470,523 filed on November 15, 1944 and issued on May 17, 1949 to Giuseppe Russo, in which the cover is made up of a rectangle of cardboard having both extreme edges curved, said cover being fixed at its central portion to the base of the matches so as to form a straight back from which depart two free edges of the cover which, coming together with their respective extremities curved above the heads of the matches, form the snap closure by means of the insertion of the edge with the smaller radius of curvature into the edge with the larger radius of curvature.

In this case the covering for the formation of the snap closure comprises a rectangle of thin cardboard having both extreme edges pre-curved, each according to a predetermined radius of curvature.

In order that such types of coverings from a practical viewpoint give an efficient snap closure it is necessary that the curved portions have suitable characteristics as to stability, elasticity and resistance to repeated use. This is ensured by using for the manufacture of the covers a thin cardboard having suitable properties and subjecting the extreme edges to a special treatment which comprises absorption of synthetic resin, and their drying and curving in a hot die so as to polymerise the resin. After this treatment, the extreme edges of the covers remain permanently curved and have also the characteristics of elasticity and resistance to continual use such as are requested for a satisfactory closure.

It is an object of this invention to provide a continuous machine which effects the curvature of either one or both of the extreme edges of book match covers of the above mentioned type, starting with rectangles of thin cardboard which have been previously printed, with the usual roughened surface, and having the edges or edge, according to the case in question, already resin treated. The automatic machine for the permanent curvature of the extreme edges of the match covers having snap closure according to the invention is characterized in that it comprises a continuous succession of curving dies, which are mounted on the links of a continuous conveyor chain, a plurality of heater elements through which pass the dies on the upper and lower section of the die carrier conveyor to effect the polymerization of the resin with which one or both extreme edges of the covers are imbibed, a pick up and insertion device for placing the cardboards in the dies, a mechanical pincer for removal of the cardboards from the dies after polymerization of the resin and a plurality of ejectors for the cardboards. It is another object of this invention to provide in the machine an orderly system of off-loading of the card-

2

boards with two curved edges, so as to arrange them, as to occupy the least possible space, within special rectangular boxes which are provided to be later mounted directly as a loading hopper on the machines which carry out the joining of the covers with the matches for the formation of the finished book matches with two curved edges.

For the covers which have only one edge curved it is provided, depending on the working method, either the off-loading with hand collection, or an off-loading into special boxes.

The basic operations carried out by the machine for the curvature of both edges of the cardboards are as follows:

15 Lifting up by means of a pneumatic suction device a cardboard from the pack of stacked cardboards which are hand loaded into the horizontal hopper.

Release of the cardboard from the suction device and its turning over horizontally, which is done by an inter-ception element.

Feed forward of the cardboard by means of pushers until it is above one of the dies on the continuous die holder conveyor.

Centering up of the cardboards above the die by means 25 of limit guides.

Insertion of the cardboard into the die and simultaneous curving of both edges by means of a pressure device which has double action spring loading.

Conveyance of the cardboard, held in the die by the 30 particular form of the die and by other means, along the polymerization path where special heater elements maintain at a predetermined temperature the curvature effecting extremity of the dies.

Removal of the cardboard from the die by means of 35 a mechanical pincer, after the polymerization of the resin has taken place.

Feed forward of the cardboard or cover which is now finished, into a special interchangeable box mounted on a surface which automatically has a rhythmical sideways 40 motion with the purpose of arranging the cardboards alternately, thus allowing maximum use of the space of the small box. The loaded boxes can thus be transferred to the next step of manufacture where they act as a loading hopper on the machine which makes up the finished booklets of matches.

In the case where the machine has to be used for production of covers with only one curved edge, it is very easy to change the machine over to this by substitution of one curving die for another.

50 The invention is described in one embodiment thereof which is given purely as an example and in no way limiting it, with reference to the attached drawings, in which:

Fig. 1 is a diagrammatic view of the whole of the machine according to the invention, in side elevation and partially in section;

Fig. 1a is an enlarged view of the release valve fitted to the pneumatic device for lifting up the cardboards from the loading hopper;

Fig. 2 is a diagrammatic plan view of the machine 55 shown in Fig. 1;

Fig. 3 is an enlarged detail view, as seen in the section along the line A—A' of Fig. 1, of the presser-curve device which inserts the small cardboard into the die and the curvature of its edges;

65 Fig. 4 is a view in perspective of the mechanism which determines the movement of the presser-curve device shown in Fig. 3; and

Fig. 5 is a cross section through the line B—B' in Fig. 1, which shows the die heater elements in the upper section and also in the lower section of the continuous die conveyor.

It is apparent that such a machine can easily be ar-

ranged or set up for working one or more series at a time. In the form described it is set for one series at a time, that is it comprises that single series of devices necessary for each of the operations above described. But to have a greater production it is possible to build the machine so as to give a multiple of the production by placing in parallel two or more series of identical devices which comprise the machine as a whole, the whole being worked simultaneously off one drive unit.

The description that follows leaves out all those parts of the machine, such as motors, main transmissions, starter devices, stopping devices, and electrical circuits etc., which are commonly found on all modern machines and which have a merely auxiliary function with regard to the devices which make up this invention.

The machine essentially comprises (Fig. 1) a continuous succession of dies (1) carried by jointed elements or links of a continuous conveyor chain 2, along whose path are carried out the steps of the curving procedure of the extreme ends of the small rectangular cardboards which are to be used as the covers for the book matches. These steps are essentially: centering of a small cardboard above the die, pressing in the die with resultant curvature of the edges, polymerization of the resin while the cardboard is held in the die as it moves along the heater section and extraction of the finished cover.

The conveyor chain carrying the dies 2, mounted on special profiled sprockets 58 and 59, moves forward with an intermittent motion. In fact the sprocket wheel 59, which is the driving sprocket, is driven through a cylindrical toothed wheel 60 keyed onto the same shaft 61, from the divider disc 62 which meshes with the cylindrical toothed wheel 60. The divider disc 62 receives intermittent impulses from the cylindrical cam 63 with a spiral on it, mounted on the shaft 88, which in its turn takes its motion from the motor of the machine through a chain 64, the sprocket 65 keyed to the shaft 66 and the bevelled gear couple 67.

The rectangular cardboards pre-treated with resin, (as well as having been already printed and fitted with rough match striker strips), are loaded by hand in a vertical side by side position into the horizontal loading hopper 3, in which the counterbalance device 4 keeps the row of cardboards against the outlet mouth of the hopper 3.

Here the small stops 5 prevent the cardboards from escaping of their own accord from the hopper mouth.

A suction operated device (Figs. 1 and 2), which is essentially made up of a pair of vacuum suckers 6-6' connected to a tube 7 which has one end terminating at the suction pump 8, takes the cardboards rhythmically, one at a time, from the hopper 3, the resistance of the stops 5 being overcome by the suctional effect on the cardboards.

The suction device for the lifting of the cardboards carries out a to and fro motion, as the tube 7 on which are fitted the sucker ends 6-6' is carried by the supports 9-9' which are connected by means of levers 10-10' to the grooved cams 11-11' keyed to the shaft 66 already described, which causes the to and fro motion of the suckers 6. For this reason the tube 7 is connected to the pump 8 by means of a flexible hose 12.

Each time that the pneumatic device taking up the cardboards shims the surface of a cardboard *a*, in the mouth of the suckers 6-6' there is a pneumatic suction created by the pump 8 which, being controlled through the lever 13 of the eccentric 14 mounted and timed on the shaft 15, starts in phase causing in the tube 7 the necessary suction effect.

In the return movement of the pneumatic lifting device, the cardboard adhering to the suckers 6-6' are intercepted by an interception element 16, which is a specially slotted and inclined plate, causing, together with the lessening of vacuum or suction effect in the suckers, the departure of the cardboards from the suckers 6-6' and

their turning over onto a horizontal plane formed by the two guides 17-17'.

The diminishing of the pneumatic suction in the suckers 6-6' at the moment of the cardboard leaving the sucker mouth, is obtained by the gradual opening of the relief valve 18 (Fig. 1a) which is fitted on the back of each of the suckers 6-6', operated by the lever 19 sliding on an inclined plane 20 in the withdrawal phase of the pneumatic device to lift up the cardboards.

Immediately after the cardboard *a* has been deposited on the horizontal guides 17-17', a pair of pushers come into action (21-21') which, having a rhythmical to and fro motion in step or timed with the pneumatic lift device for the cardboards, push the cardboard *a* until it is above one of the dies on the continuous conveyor 2.

The to and fro movement of the feeder pushers 21-21' (Fig. 1) is imparted by the lever 22 operated from the grooved cam 23 which is keyed to the shaft 15 on which is also keyed an eccentric 14 for the movement of the pump 8, already described.

The exact centering of the cardboard *a* pushed into place by the pushers 21-21' over the die 1 is obtained by two lateral guides 24-24' (Fig. 3) and by the stop or small end of travel plate 25 (Fig. 1), which are adjustable.

At the moment that the cardboard *a* becomes centered above the die 1, the die conveyor chain 2 starts a short rest period between two successive moves forward. It is during this short rest period that the presser device 26 effects, during the lowering phase of the vertical alternating motion which it carries out, the insertion of the cardboard *a* into the die 1 with the necessary curvature of the extreme edges.

The presser device 26 (Fig. 3) is made up of two main parts: a presser foot 27 fitted to a small spring loaded piston 35 sliding in the body of the presser 26 which first starts its action by pressing the cardboard *a* in the central portion above the die 1 thus holding it firmly in position, and a pair of articulated arms 36-36' which successively sliding along the two edges of the cardboard press them forcing the edges to enter into the curved over extremities of the die 1 and to adhere to their rounded shape.

The travel of the small spring loaded piston 35 is sufficiently great to allow the curvature arms 28-28' to open, more or less, according to the length of the die 1 or that is the length of the cardboard *a*.

During the upwards motion of the presser device 26, the pivoted arms 28-28', due to the effect of the springs 37-37', return to their original position; the presser foot 27 does the same, due to the effect of the spring 38.

The vertical up and down motion of the presser device 26 is caused (Fig. 4) by the grooved cams 29-29' keyed onto the shaft 15 and which by means of the small rollers 30-30', the levers 31-31' and the rods 32-32' sliding within the sleeves 33-33', impart to the traverse 34 on which is fitted the presser device 26, the necessary vertical alternating motion. Naturally, when one changes from one size die to another, that is when one changes the size of cardboard in length, it is necessary to also change the cams 29-29' with another pair of cams which are suitable for obtaining the necessary travel of the presser device 26.

As soon as the presser device 26 is withdrawn from the die 1 leaving the cardboard inside the die, the continuous conveyor chain 2 (Fig. 1) moves forward one place thus allowing the same presser device 26, in the next cycle, to effect the insertion of another cardboard into the next die in the line.

Every die 1 (Fig. 5) is formed of a metallic plate whose extremities 39-39' are formed in a semi-circle according to the different radii of curvature, corresponding to the radii of curvature which one wishes to give to the two edges of the cover *a*. The curved semi-circular part of the two extremities 39-39' is extended in the upper part of the die for a short straight section parallel to the

plane of the die so as to hold with greater security the cardboard during the lower run of the continuous conveyor chain 2 when the dies are overturned. In the central part of every die are fitted, on the side opposite to the direction of feed motion, two studs or pins 40—40' which serve to keep the cardboards centered in the die during the motion forward of the chain 2 and in particular to stop the cardboard from slipping out of the die and falling to the ground when it is in a vertical position at that point on the chain conveyor 2 where the removal of one of the cardboards occurs by the pincers.

At the other point on path of the conveyor chain 2 (Fig. 1), where the cardboards in the dies find themselves in a vertical position a special spring described later prevents them from falling out of the dies.

Each die 1 (Fig. 5) is fitted to an element of the chain conveyor 2 by means of two screws 116—116' countersunk in grooves 117—117' having rectangular section which allow the point of one of the fingers of the pincer extracting the cardboards from the dies to penetrate between the die 1 and the under side of the cardboard *a*.

The polymerization of the resin treated edges of the cardboards is obtained by heat from suitable heater elements. In the upper section of travel of the continuous conveyor chain 2 the dies pass between heater elements 41—41' (Fig. 5) which are shaped so as to embrace completely the curved portions 39—39' of the dies 1. In the lower section of travel of the continuous conveyor chain 2, the heater elements 42—42' (Fig. 5) are of rectangular section and against these rub only the extreme edges of the dies 1. The sole reason for this is to allow the die conveyor 2 to be free to form easily the catenary on the lower section, but naturally it is possible to vary in any manner the form of the heater elements without departing from the scope of the invention.

The heater elements 41—41' and 42—42' are fitted to the frame of the machine by means of brackets 105—105' which have holes 106—106' and fixing screws 107—107' so as to allow for adjustment in width of the heater elements 41—41' and 42—42' so as to fit them to the length of the dies being used.

The heater elements 41—41' and 42—42' use tubular electrical resistances 43—43' as a source of heat. The resistances 43, that is those fixed to one side of the machine, are fed independently from the resistances 43' so as to exclude one or the other when the machine is being used for production of covers for book matches having only one edge curved.

The total length of the heating section (Fig. 1) works for such time as is needed to complete the polymerization of the resin in relation to the temperature applied and to the speed of movement of the dies.

For control and automatic regulation of the temperature for the heater elements (or of the dies) on each side of the machine, a normal thermo-regulator apparatus 44 is used, having minimum and maximum current contacts.

In order to assure the stability of the cardboards in the dies and their adherence to the curved portion of the dies, apart from the particular form of the curved extremities 39 and 39' of the dies and the studs or pins 40—40' which have been already described, on the polymerization section the following extra arrangements have been provided:

A continuous rectangular cross-section bar 45 (Fig. 5) placed lengthwise along the center line of the dies 1 in the upper heater section, at a distance from the dies which is little more than the thickness of the cardboards, so as to stop the central part of the cardboard raising itself due to heat effect, thus creating the eventual drawing back or escape of the curved edges from the curving extremities 39—39' of the dies.

One or more spreading devices 46 (Fig. 5 and Fig. 2) placed on the upper travel of the conveyor 2 and fixed

to the small bar 45 above described, made up of hinged arms which are spring loaded 47—47' on whose ends are small circular profiles bars 48—48' which assure the adherence of the edges of the cardboards against the semicircular heated surfaces at the extremities 39—39' of the dies.

The spring plates 49 and 50 fitted to the bar 45 which is placed on the center line of the succession of dies 1 in the section where the continuous conveyor chain 2 follows into the curve while passing from the top to the lower portion of the travel. The spring 50 being long enough to embrace the dies during the whole curved section of the travel is also fixed at the bottom, at its other end, to the frame of the machine.

The springs 49 and 50 prevent the cardboards falling out of the dies to the ground when these get into the vertical position since the small stop studs 40 and 40' are on this curve section, in the upper part of the dies.

The spring plates 51 and 51' (Figs. 1 and 5), which are suitably fitted to the end of the frame of the machine, are placed parallel against the bottom of the dies 1 so as to hold the cardboards *a* in position and thus stop eventual escape and falling away.

When a die which is loaded (Fig. 1), reaches the vertical position on the off-loading side, the mechanical pincer 52 lowers until the end of one finger enters the grooves 117—117' in the die 1. Pincer 52, then takes hold of the cardboard *a*, extracting it from the die 1, withdrawing it in the opposite direction to the stops 40 and lifts it vertically until the series of pushers 53 (Figs. 1 and 2) come into action. At this moment the pincer 52 starts to open leaving the cardboard free so that it can be collected by the ejector pushers 53 and pushed forward into the vertical lying down position within the channel 55 where the cardboards pushed one against the other, are made to enter a special interchangeable collector box 56. In order however to collect the covers with curved or bent over edges on an orderly basis and so as to exploit to a maximum the space available in the box 56, the off-loading table 57, on which is mounted the channel 55 and the box 56, makes a rhythmical sideways movement with respect to the direction of travel of the cardboards so that at each move forward of the pushers 53, the covers arrange themselves alternatively, at the two ends, with the curved edges placed one against the other, in such a way that each curved edge is in contact with the flat part of the preceding or following cover.

The mechanical pincer 52, which is fitted with forked arms so as to give a better hold on the cardboards is made (Fig. 1) of a fixed arm 68 and a mobile arm 69. The pincer 52 is fitted to the central portion of the traverse 70 which is mounted at its two ends (Fig. 2) on the lifting rods 71—71' which are connected at their lower ends to a lever 73 actuated by a grooved cam 74 which is keyed to the shaft 66, and carry out a rhythmical up and down motion carrying with them the traverse 70 on which is fitted the mechanical pincer 52.

The opening and closing of the pincer 52, whose fingers 68 and 69 tend to keep closed due to the spring 75 (Fig. 1), happen during the up and down motion of the traverse 70 by means of the extension 76 of the mobile arm 69. This extension 76 carries at its end a smaller roller 77, which, running on the fixed inclined surface 78 during the step of the upward motion of the traverse 70, causes the opening of the fingers of the arms 68—69.

In the lowering phase of the traverse 70, with the running of the roller 77 on the inclined surface 78, the spring 75, which is a return action spring, causes the gradual closure of the arms 68—69 but, at the moment at which the pincers 52 have to take hold of the cardboard *a*, that is during the last part of the descent section, the roller 77 finds itself rolling on a more sharp portion of the cam 79 which forces the arms 68—69 to move

in the instant in which these are placed before and after the cardboard *a* and then close fast on the cardboard. The cam 79 is semi fixed, that is it can partially turn in either direction, whether clockwise or counter clockwise, and thus remains immobile during the descent step of the roller 77 forcing it to follow its shape.

In the upwards step, however, when the roller 77 is again in contact with the cam 79 it manages to overcome the tensional force of the spring 80 and causes the cam 79 to turn enough to pass it undisturbed, without, however, interrupting the gripping action of the fingers or arms on the cardboard *a*.

Thereafter the roller 77 has to again return up the inclined surface 78 and it is, in fact, in that moment when the gripping fingers or arms 68-69 open, leaving the cardboard *a* free, to be collected by the pushers 53 which have timely arrived after their horizontal to and fro motion.

The pushers 53 at that point where they come into contact with the cardboards, are bent at right angles and the horizontal section 53, which is bevelled to facilitate their insertion under the cardboards, penetrates into a special hollow 81 cut into the bottom of the channel 55 in which the cardboards are collected and directed to the box 56.

The pushers 53 are fitted to the traverse 82 (Fig. 2) which slides on the guides 83-83'. The to and fro motion is given to the traverse 82 by the play of the levers 84-85 and 84'-85' (Figs. 1 and 2) which are actuated respectively off the grooved cams 86-86' which are keyed on the shaft 87 in its turn connected to a suitable transmission and to the motor of the machine. As already explained, the off-loading surface 57 on which is secured the channel or groove 55 and the collector box 56 (Fig. 1) moves rhythmically in a cross direction to the machine so as to allow the staggering of the curved edges for an orderly collection of the finished covers. Such an alternating cross motion is obtained due to the oscillating movement of the lever 89 to whose upper end is attached the slide 90 which runs in the guide 91. To the slide 90 is secured the off-loading surface 57. The lever 89 carries out the oscillating motion which causes the cross shift or movement of the surface 57, it being pinned at the center at 89' and actuated from the other end by a grooved cam 92 which in its turn takes its movement (Fig. 1) from the shaft 88, already described, through a pair of toothed cylindrical wheels or gears 93 and 94 and the coupling 108.

However, since the sprocket 93 is mounted idle on the shaft 88, it is possible, by means of the coupling 108, which is controlled by hand through the lever 109, to eliminate at will the alternating cross motion of the off-loading surface 57 when this motion is not desired, as for example when the machine is being used for production of book match covers which have only one edge curved.

The box 56 can be easily fixed to the off-loading surface 57 and also easily removed from it, causing it to slide within the lateral guides 98-98' which are secured to the surface 57 by means of the screws 110-110' (Fig. 2) which slide inside the hollows 111-111' so as to accommodate the differences of width of the boxes 56.

The width of the boxes 56 and the insertion channel 55 is determined by the length of the finished covers and by the amount of the travel effected by the surface 57 for the arrangement of the curved edges of the cards.

The arrangement of the off-set cardboard covers in finished state in the collector box 56 is clearly shown in Fig. 2.

While only some embodiments of invention have been shown and described it is obvious that various modifications can be made without departing from the scope and the true spirit of the invention.

I claim:

1. In an automatic machine for permanently curving

and polymerizing a resin treated edge of each of a plurality of deformable members, a die movably mounted on the machine, said die comprising a metallic forming plate having a forming edge of the contour to which the edges of the deformable members are to be formed, said forming edge being curved over upon said forming plate to form an arcuate end member, said edge of said die being heated for heat treating the edges of the deformable members, means mounted on the machine for placing the deformable members into said die, and means mounted on the machine for pressing an edge of the deformable members into said forming edge of said die, said pressing means comprising a press element for holding the deformable members in said die and an arm pivotally mounted on said pressing means on one side of said element to extend transversely therefrom for engaging the deformable members within said die and upon movement of said pressing means toward said die being actuated outwardly from said element toward said end member thereby forcing the edge of the deformable member into said end member of said die.

2. In an automatic machine for permanently curving and polymerizing a resin treated edge of each of a plurality of deformable members, a plurality of dies movably mounted on the machine, each of said dies comprising a metallic forming plate having forming edges of the contour to which the edges of the deformable members are to be formed, said forming edges being curved over upon said forming plate to form arcuate end members, said edges of each of said dies being heated for heat treating the edges of the deformable members, means mounted on the machine for placing the deformable members into said dies, and means mounted on the machine for pressing the edges of the deformable members into said forming edges of said dies, said pressing means comprising a press element for holding the deformable members in said dies and a pair of arms pivotally mounted on said pressing means, one on each side of said element to extend transversely therefrom for engaging the deformable members within said dies and upon movement of said pressing means toward said dies being actuated outwardly from said element toward said end members thereby forcing the edges of the deformable members into said end members of said dies.

3. In an automatic machine for permanently curving and polymerizing a resin treated edge of each of a plurality of deformable members, a plurality of dies movably mounted on the machine, each of said dies comprising a metallic forming plate having forming edges of the contour to which the edges of the deformable members are to be formed, said forming edges being curved over upon said forming plate to form arcuate end members, said edges of each of said dies being heated for heat treating the edges of the deformable members, means mounted on the machine for placing the deformable members into said dies, means mounted on the machine for pressing the edges of the deformable members into said forming edges of said dies, said pressing means comprising a plunger for holding the deformable members in said dies and a pair of arms pivotally mounted on said pressing means, one on each side of said plunger to extend transversely therefrom for engaging the deformable members within said dies and upon movement of said pressing means toward said dies being actuated outwardly from said plunger toward said end members thereby forcing the edges of the deformable members into said end members of said dies, and spring means mounted on said pressing means for biasing said arms toward said plunger upon removal of said pressing means from said dies.

4. In an automatic machine for permanently curving and polymerizing a resin treated edge of each of a plurality of deformable members, a plurality of dies movably mounted on said machine, each of said dies comprising a metallic forming plate having forming edges of the

contour to which the edges of the deformable members are to be formed, said forming edges being curved over upon said forming plate to form semi-circular end members, said edges of each of said dies being heated for heat treating the edges of the deformable members, means mounted on the machine for placing the deformable members into said dies, means mounted on the machine for pressing the edges of the deformable members into said forming edges of said dies, said pressing means comprising a plunger spring biased for holding the deformable members in said dies and a pair of arms pivotally mounted on said pressing means, one on each side of said plunger to extend transversely therefrom for engaging the deformable members within said dies and upon movement of said pressing means toward said dies being actuated outwardly from said plunger toward said end members thereby forcing the edges of the deformable members into said end members of said dies, and spring means mounted on said pressing means for biasing said arms toward said plunger upon removal of said pressing means from said dies.

5. In an automatic machine for permanently curving and polymerizing a resin treated edge of each of a plurality of cardboards for book match covers fed by a feeding device mounted on said machine comprising a plurality of dies movably mounted on said machine, each of said dies comprising a metallic forming plate having a forming edge of the contour to which one edge of the cardboards is to be formed, said forming edge of each of said dies being curved over upon said forming plate to form an arcuate end member having a shape corresponding to that of the edge of the book match covers to be formed, a presser unit mounted on said machine comprising a reciprocating housing in which a spring biased plunger is slidably mounted, said plunger being actuated against its spring for moving a cardboard from the feeding device into said dies and for holding the cardboard in said dies, and an arm pivotally mounted on said housing transversely to said plunger for engaging the cardboard between said plunger and said curved edge of said dies, said arm upon relative movement of said housing with respect to said plunger toward said dies sliding on the cardboard away from said plunger toward said curved edge of said dies forcing the edge of the cardboard into said forming edge of said dies, said arm being spring biased toward said housing and being actuated toward said housing upon removal of said plunger from said dies.

6. In an automatic machine for permanently curving and polymerizing two opposite resin treated edges of each of a plurality of cardboards for book match covers

fed by a feeding device mounted on said machine comprising a plurality of dies movably mounted on said machine, each of said dies comprising a metallic forming plate having two opposite forming edges of the contour to which the two edges of the cardboards are to be formed, said forming edges of each of said dies being curved over upon said forming plate to form arcuate end members each having a shape corresponding to that of the edges of the book match covers to be formed, a presser unit mounted on said machine comprising a reciprocating housing in which a spring biased plunger is slidably mounted, said plunger being actuated against its spring for moving a cardboard from the feeding device into said dies and for holding the cardboard in said dies, and a pair of arms pivotally mounted on said housing transversely to and one on each side of said plunger for each engaging the cardboard between said plunger and one of said curved edges of said dies, said arms upon relative movement of said housing with respect to said plunger toward said dies sliding on the cardboard away from said plunger toward said curved edge of the cardboard into said forming edge of said dies, said arms being spring biased toward said housing and being actuated toward said housing upon removal of said plunger from said dies.

7. The combination set forth in claim 6 wherein said forming edges of said dies have different radii of curvature for forming book match covers having edges adapted to be nested.
